UNITED STATES PATENT OFFICE.

JOSEPH H. BEARD, OF TOLEDO, OHIO.

DEVICE FOR TRIMMING REEDS OF MUSICAL INSTRUMENTS.

Application filed August 27, 1927. Serial No. 215,795.

This invention relates to means for trimming the ends of reeds of musical instruments and the like, and has for one of its objects the provision of a portable and simply constructed trimmer that may be readily carried in the pocket of a player and used without leaving his seat, as in an orchestra.

Musicians have found that the reeds utilized in playing clarinets, saxophones, 10 and other similar instruments will not long retain the desired thin, smooth edge requisite to securing the best tones from the instruments, the thin tip of the reed becoming cracked or notched during use, while 15 it is possible to restore the tip of the reed to its previous condition by trimming with an edged tool such as a penknife, it is extremely difficult for the average user to so trim the reed. 20 Either the shape of the reed's tip is altered so as to interfere with its re-use in playing, or a much too large portion is trimmed from the tip, resulting in the rapid shortening of the reed to the point where it can no 25 longer be secured upon the instrument, or both, occur when reeds are trimmed by unskilled operators. An object of my invention is to provide an instrument for trimming the thin tips of reeds that can be readily used by unskilled operators, and whereby 30 the desired shape of the reed's tip may be accurately maintained. Also my instrument permits the paring of a very minute portion from the edge of the reed's tip and permits the operator to see at all times just 35 how much is being trimmed from the reed.

Other objects and advantages will be apparent from the following description wherein reference is made to the accompanying drawings illustrating a preferred embodiment of my invention and wherein similar reference numerals designate similar parts throughout the several views.

In the drawings:

45 Figure 1 is a plan view of my improved trimming device with a reed in position for the trimming operation.

Figure 2 is a central longitudinal section therethrough, and

50 Figure 3 is a view similar to Figure 2, showing the position assumed by the reed and trimming device after the desired portion has been pared from the reed.

Referring now to the drawings, the numeral 5 designates a plate forming the body 55 of my improved trimming device and formed adjacent one extremity with a curved slit 6 and an integral cutter member 7 shaped to accurately fit into the curved slit 6 but severed from the plate 5 on all but one side 60 (note Figure 2). The plate 5 is preferably formed of metal, as for example, spring brass or steel; and the adjacent edges of the cutter 7 and slit 6 are formed so as to closely align with each other when the cutter member 65 is in the plane of the plate 5 during the cutting operation (note Figure 3). The ends of the plate beyond the unsevered side of the cutter member is normally bent upwardly, substantially as shown in Figure 2, the cutter 70 member remaining in the plane of the center of the plate. The size of the plate 5 is such that it will conveniently fit in a vest pocket, purse or the like, and is preferably made but slightly longer than the 75 usual length of reeds used on musical instruments. To aid in forming the cutter member 7 and slit 6, I preferably provide a pair of apertures 8 in the plate 5 at the extremities of the slit and comparatively 80 close to the side edges of the plate, the end of the plate beyond the aperture being thereby provided with a hinge, or portion on which it flexes, of lesser width than that of the cutter member.

In use the reed to be trimmed, as 9, is arranged with its under side resting upon the upper surface of the plate 5 and with its thin tip extending through the slit 6 into contact with the under side of the upwardly bent end of the plate 5, substantially as shown in Figures 1 and 2. The extent of the tip's edge desired to be trimmed can be readily determined by sliding the reed back and forth upon the plate 5 until only the portion desired to be removed contacts with the under side of the plate. In this way a very minute slice can be taken from the tip of the reed, and the slice to be removed is at all times visible to the operator. While the 90 cutter member 7 may be struck up from the plane of the plate 5, I preferably leave the cutter member in the plane of the body portion of the plate, and bend upwardly the end of the plate so that the end wall of the 95 slit extends upwardly a lesser distance than

the ordinary thickness of the reed's tip, and accordingly it is necessary to slightly spring upwardly the end of the plate in inserting the tip of the reed into the position shown in Figures 1 and 2. This results in giving a spring pressure upon the tip of the reed to aid in holding it during the aligning and cutting operations, and the body portion of the reed can be similarly held against the 10 plate 5 by a thumb or finger of the operator. To insure the accurate positioning of the reed within the slit 6 so that the cutting operation will give the desired shape to the tip after a portion has been removed therefrom, I preferably provide a series of parallel lines 10 upon the upper surface of the 15 plate 5. The sides of the reeds used are ordinarily parallel and can be readily aligned with one or another set of the lines 20 10 according to the width of the reed to be trimmed. After the tip of the reed has been inserted into the slit 6 to the desired extent and the sides of the reed have been adjusted to bring them into parallelism with 25 one or another set of lines 10, the desired portion is cut from the reed by pressing the end of the plate 5 from the position shown in Figure 2 to substantially the position shown in Figure 3. Or in other words, the 30 end of the plate 5 is pressed into re-alignment with the plane of the cutter member 7, bringing the free edge of the cutter member and the wall of the slit 6 into alignment, shearing the portion below the end of the 35 plate 5 from the remainder of the reed. It is to be understood that the shape of the slit 6, and particularly the intermediate portion thereof, is in accordance with the desired shape for the reed's tip.

40 While it is possible to construct a slit 6 and cutter member 7 of sufficient width to trim practically all of the reeds ordinarily used upon musical instruments, I have found it difficult, with a very wide cutter member, 45 to retain the desired shape upon the tip of the comparatively narrow reeds when trimmed therein. Accordingly I preferably provide a plurality of slits and cutter members for trimming the narrower reeds and 50 vice versa. In the illustrated embodiment of my invention I have shown a pair of slits and cutter members, the slit 6 and cutter member 7 being arranged for comparatively narrow reeds while the slit 6^a and 55 cutter member 7^a are arranged for trimming comparatively wide reeds. Moreover, the arrangement is such that the same set of par-

allel lines 10 may be utilized for aligning the sides of reeds to be trimmed by either cutter member 7 or 7^a.

60

From the above it will be apparent that I have provided a trimming device of great simplicity, that may be readily used by unskilled operators to trim reeds of various widths to the desired shape, and whereby very minute portions may be trimmed from the tips of the reeds. Moreover, the entire device is of such size that it can be readily transported in the pocket or purse of an operator and the trimming operation can be 70 performed at any place without the need of special tools other than my improved trimming device.

65

While it will be apparent that the illustrated embodiment of my invention herein disclosed is well calculated to adequately fulfill the objects and advantages primarily stated, it is to be understood that the invention is susceptible to variation, modification and change within the spirit and scope of 80 the subjoined claims.

75

What I claim is:

1. In a device of the character described, a body plate of resilient metal having formed therein a curved slit and a pair of 85 apertures at the extremities of the slit, an integral cutter member arranged with its free edges conforming to the walls of said slit the end of the plate beyond the apertures being adapted to flex relatively to the cutter member on a line joining the said apertures, the end of the plate being bent to normally extend out of the plane of the center of the body plate, and a plurality of parallel guide lines arranged on the surface of the plate to 90 facilitate accurate positioning within the slit of the material to be cut.

95

2. In a device of the character described a body plate of resilient metal having formed 100 therein a pair of curved slits of different widths adjacent the opposite ends of the body plate and a pair of apertures at the extremities of the slits, an integral cutter member arranged with its free edges conforming to the walls of said slits, the ends 105 of the body plate beyond said slits normally extending out of the plane of the cutter member, and a plurality of parallel lines arranged on the surface of the plate to facilitate accurate positioning of the material to 110 be cut within either of said slits.

105

In witness whereof I hereunto set my hand.

JOSEPH H. BEARD.
